UNITED STATES PATENT OFFICE.

HERMAN A. ERICKSON, OF BAKERSFIELD, CALIFORNIA.

LAPPING MACHINE.

Application filed August 2, 1921. Serial No. 489,160.

To all whom it may concern:

Be it known that I, HERMAN A. ERICKSON, a citizen of the United States of America, and a resident of Bakersfield, county of Kern, State of California, have invented certain new and useful Improvements in and Relating to Lapping Machines, of which the following is a specification.

This invention relates to certain improvements in lapping machines; and the nature and objects of the invention will be readily understood by those skilled in the art in the light of the following explanation and detailed description of the accompanying drawings illustrating what I now believe to be the preferred embodiments or mechanical expressions of the invention from among other forms, arrangements, combinations and constructions within the spirit and scope thereof.

The present invention relates particularly to machines for lapping the cylinders, pistons and piston rings of internal combustion motors of the automobile type, although the invention is equally applicable to use in lapping the cylinders of all types of internal combustion motors, as well as cylinders generally.

Those familiar with the use and repair of automobile internal combustion motors are aware of the great difficulties encountered in lapping scored and scratched cylinders and in lapping pistons and piston rings to the cylinders with which they are to be operated. According to one of the generally prevailing methods and practices at present in use in repair shops, garages and such like, the lapping of scored and damaged cylinders is performed manually by reciprocating the piston in the cylinder to be repaired until the grinding and abrasive action of the contacting surfaces has effaced the scores, scratches or other damage, from the cylinder wall, or in the case of lapping pistons and piston rings, until the piston and rings have been ground sufficiently to provide the necessary tight, leak proof fit with the cylinder. It is well understood by those skilled in this art, that the most efficient method of performing this lapping operation is to rotate the piston while reciprocating the same in the cylinder, in order to uniformly distribute the grinding action around the contacting surfaces and prevent grinding the cylinder and piston out of alinement. Obviously, this manual method

of lapping is a lengthy, tedious operation and cannot be performed with the desired degree of accuracy because of the difficulty of evenly grinding around the cylinder wall and maintaining the required alinement manually. Further, it is usually necessary to practically completely disassemble the motor to be repaired and to remove the damaged cylinders in order to manually work thereon.

One of the main objects of the present invention is to overcome the various disadvantages and difficulties above referred to as present in the existing practices of manually lapping cylinders and pistons, by providing a machine for lapping the cylinders, pistons and rings of automobile internal combustion motors without requiring complete disassembly of the motor or the removal of the cylinders from the motor, and which machine is portable and readily moved and placed into operative position with respect to the motor to be repaired.

A further object of the invention is to provide a machine for lapping the cylinders, pistons and rings of internal combustion motors by imparting a reciprocatory movement to the piston in the cylinder to be operated upon and which machine at the same time automatically imparts a rotary movement to the piston at regular intervals with respect to the reciprocation.

A further object of the invention is to provide a machine for lapping the cylinders, pistons and piston rings of internal combustion motors, with universal connections for coupling the piston of a cylinder to be lapped with the machine, so that the piston and cylinder will be maintained in proper alinement for lapping without necessitating the machine and connections being alined with the cylinder and piston.

A further object of the invention is to provide a machine for lapping the cylinders, pistons and piston rings of automobile internal combustion motors, which may be placed beneath, or above, a motor without removing the same from the automobile and connected with the pistons to lap the cylinders by imparting a combined reciprocation and rotary movement to the pistons while maintaining them in proper alinement without regard to the alinement of the machine with respect to the cylinders.

A further object of the invention is to provide improved mechanism for imparting

a combined reciprocatory and rotary movement to the piston of a cylinder, which is of few parts of simple construction and arrangement, positive in operation and efficient in results.

With these and other objects in view, the invention consists in certain novel features in construction and in combinations and arrangements as more fully and particularly set forth and specified hereinafter.

Referring to the accompanying drawings:

Fig. 1 is a top plan view of a lapping machine embodying features of the invention.

Fig. 2 is a view in side elevation of a machine of the invention, showing more or less diagrammatically, a cylinder and piston operatively connected therewith.

Fig. 3 is a detail side elevation, partly in vertical section, of the connecting means and operating mechanism therefor.

Fig. 4 is a detail perspective view showing certain parts of the invention.

Fig. 5 is a detail side elevation.

Fig. 6 is a side elevation of the rotary crank disk of the machine of the invention.

In the particular form and embodiment of the invention illustrated herewith, the machine is mounted upon a portable supporting frame 1, comprising the side bars 2 having their opposite end lengths bent to provide the legs 2^a and maintained parallel and rigidly spaced apart by the end bars 3 secured at their opposite ends to and connecting the side bars 2. A bar 4 is secured longitudinally of the frame 1, parallel with and spaced a distance from one of the side bars 2, and secured at its ends to the end bars 3. Suitable parallel and spaced braces 4^a are secured between the bar 4 and the side bar 2 adjacent thereto.

The supporting frame 1 may be formed of any comparatively light, inexpensive material, such for example as strap iron, although it is to be understood that any desired or suitable frame or other mounting may be utilized, as it is not intended or desired to limit the invention to the type or form of mounting used in connection therewith.

The mechanism of the invention comprises the shaft 5 journaled in the alined bearings 5^a mounted on the bar 4 and the side bar 2, respectively, between the braces 4^a. The outer end of the shaft 5 is provided with the driving wheel 6 mounted thereon, and in the particular example illustrated is in the form of a gear wheel adapted to be rotated from any suitable or desired source of power (not shown). The inner end of the shaft 5 has the crank disk 7 mounted thereon and rotatable therewith. The crank disk 7, as clearly shown in Fig. 6, of the drawings, is provided with a series of spaced, transverse bores 7^a therethrough at intervals

from the center toward the periphery of the disk. A crank pin 8 provided with a reduced shank portion 8^a is adjustably mounted on the crank disk 7 with the shank 8^a fitting in one of the bores 7^a and extending 70 a distance beyond the disk 7, where it is screw threaded to receive the securing nut 8^b for locking the crank pin to the crank disk. The crank pin 8 may be secured in that bore 7^a which is at the distance from 75 the center of the disk to give the required throw to the crank pin 8 when the disk 7 is rotated by the shaft 5 and drive wheel 6. Any number and desired arrangement of 80 bores 7^a can be provided through the disk 70 to permit mounting the crank pin at various distances from the center of the crank disk to vary the throw of the pin to meet the requirements of the operation to be performed.

The crank pin 8 is provided with a groove 9 therein and extending therearound at an angle to the axis of the pin, that is, the plane of the groove 9 lies at an angle to a transverse plane through the pin at right angles 90 to the axis thereof. A collar 10 is loosely mounted and confined in the groove 9, and is formed in two sections for removal from and replacement in the crank groove 9. The sections of which the collar 10 is formed 95 are each provided with a notch 10^a cut in the edge adjacent one end thereof, and the ends of the sections are formed with screw threaded bores 10^b which are in alignment when the collar is assembled to receive the 100 securing screws 10^c, the heads of which lie and are accessible in the notch 10^a of each section, respectively, of the collar 10, as clearly illustrated, in Figs. 3, 4 and 5 of the drawings. The collar 10 is loosely mounted 105 and secured in the groove 9 of the crank pin 8 by the screws 10^c, and is provided with the diametrically opposite, peripheral recesses or depressions 10^d.

A forked member 11 is provided with opposite, alined bearing screws 11^a extending transversely through the opposite arms thereof and this member 11 is pivotally mounted on and connected with the collar 10 in the crank pin groove 9, by the bearing screws 11^a which extend into the opposite recesses 10^d in the collar 10. In this manner the forked member 11 is confined on and in pivotal connection with the collar 10. The head of the forked member 11 provides a socket 11^b to receive the ratchet 12 which is confined in the socket 11^b by a bearing block 13 removably secured in and closing the open end of the socket by a set screw or the like 13^a. The bearing block 13 is formed 110 with a central bore in which the ratchet shaft 12^a is rotatably journaled and extends outwardly a distance therebeyond. A pawl 14 is mounted in the extension 14^a at one side of the socket 11^b in operative connec- 115

tion with the ratchet 12 and with the forked member 11.

A connection rod 15 is formed with an internal bore or socket 15^a to fit over and receive the end of the ratchet shaft 12^a and is adjustably secured thereon by a set screw 15^b. The opposite end of the connecting rod 15 is flattened and provides an eye 15^c. A wrist pin connecting link 16 is provided with the spaced arms 16^a which fit over the eye 15^c of the connecting rod and are provided with alined bores through which a bolt 16^b is passed and which bolt extends through the eye 15^c to pivotally couple the wrist pin connecting link to the connecting rod 15. The opposite end of the link 16 is provided with an eye 16^c, disposed at right angles to the axis of the bores through the spaced arms 16^a, and which is adapted to be pivotally mounted on the wrist pin of a piston.

In Fig. 2 of the accompanying drawings, I show more or less diagrammatically by way of illustration, a cylinder C mounted and rigidly clamped in the vise V and having the piston P therein. The frame 1 upon which the hereinbefore described mechanism is mounted, is placed below the cylinder and the connecting link 16 is pivotally mounted on the wrist pin W of the piston P by the eye 16^c of the link. The opposite end of the link is pivotally connected to the eye 15^c of the connecting rod 15 by means of the bolt 16^b. The connecting rod 15 is adjustably coupled to the ratchet shaft 12^a by the set screw 15^b to permit the proper length or extent of connecting rod and ratchet shaft between the piston P and the crank pin 8 on the crank disk 7. Depending upon the cylinder and the particular operation to be performed thereon, the crank pin 8 is secured in the proper bore 7^a in the crank disk 7 to give the required throw to the crank pin and desired stroke to the connecting rod 15 and piston P connected therewith.

It will be noted, that, due to the universal connection provided between the wrist pin W of the piston P and the connecting rod 15, by the link 16, it is not necessary to aline the connecting rod, ratchet and crank with the cylinder C to be operated upon. Further, due to the pivotal connection between the forked member 11 and the crank pin and collar 10, the range of operation in non-alinement is still further increased without affecting the actual alinement of the piston P in the cylinder C and of the contacting surfaces therein, so that the cylinder and piston will be lapped in proper alinement without regard to the position of the frame 1 and the operating mechanism supported thereon.

In operation, with the machine of the invention connected with the piston P, as de-

scribed above, the drive wheel 6 is rotated by any suitable source of power (not shown) and rotates the shaft 5 and crank disk 7. As the crank 7 rotates, the crank pin 8 is raised and lowered to reciprocate the piston P in the cylinder C, through the collar 10, forked member 11, ratchet shaft 12^a, connecting rod 15, and link 16, as will be clearly understood by reference to the foregoing description in connection with the accompanying drawings.

As hereinbefore pointed out, to efficiently and accurately lap a cylinder, or a piston and rings to a cylinder, it is necessary to impart a rotary or turning movement to the piston, as well as the reciprocating movement, in order that the grinding action of the contacting surfaces will be evenly distributed therearound.

The present invention provides the ratchet mechanism for rotating the piston P in the cylinder C. As the crank pin 8 is moved around and upwardly and downwardly, by the rotation of the crank disk 7, the collar 10 which is loosely mounted and confined in the angularly disposed crank pin groove 9 is maintained in substantially fixed position against rotation by the forked member 11 and the crank pin 8 rotates therein with respect thereto. Due to the angular position of the groove 9 with respect to the pin 8, as the pin is moved around by the rotation of the disk 7, the groove 9 will act as a cam groove and oscillate the collar 10 and forked member 11 pivotally connected therewith. Each revolution of the crank disk 7 and pin 8 will cause one complete oscillation of the collar 10 and member 11, and the movement of the member 11 in one direction causes the pawl 14 to engage a tooth of the ratchet 12 and rotate the same, and the movement of the member 11 in the opposite direction draws the pawl across the ratchet 12 into position to engage the ratchet upon the next rotation of the disk 7 and pin 8. The rotation of the ratchet 12 by the pawl 14, rotates the ratchet shaft 12^a, connecting rod 15 and through the link 16 imparts the desired turning movement to the piston P. Thus it is seen that for each revolution of the crank disk 7 and double stroke of the connecting rod 15 and piston P, the piston P is given a partial rotation in the cylinder, and that the piston is turned a complete revolution upon a certain number of strokes by the connecting rod and piston, so that, the grinding action of the contacting surfaces is evenly distributed therearound and great accuracy is obtained.

The machine described hereinbefore may be mounted in various ways, without departing from the spirit and scope of the invention, and it is to be understood that the application illustrated in Fig. 2, is purely

by way of example. The lapping machine can be placed under a motor and operate upon a cylinder without requiring disassembly of the motor, or as in the case of V type motors can be placed above the motor and operate upon the cylinders, or if desired or necessary a cylinder can be operated upon in a horizontal position.

Being of simple, light construction and arrangement, the invention is particularly applicable to use in garages and repair shops, as it may be readily transported from one job to another.

It is evident that various changes, modifications and variations might be resorted to without departing from the spirit and scope of the invention, and hence I do not wish to limit the invention to the exact disclosures hereof.

Desiring to protect my invention in the broadest manner legally possible, what I claim is:

1. A lapping machine comprising a supporting frame, a drive shaft mounted thereon, a crank disk mounted on and rotated by said shaft, a crank pin secured on said disk and having an angularly disposed circumferential groove formed therein and therearound, a collar loosely mounted and confined in said groove, a connecting rod coupled to and reciprocated by said collar, and means operated by said collar and groove to rotate said connecting rod in one direction upon rotation of the crank disk and pin.

2. A lapping machine comprising a supporting frame, a drive shaft mounted thereon, a crank disk mounted on and rotated by said shaft, a crank pin secured on said disk and having an angularly disposed circumferential groove formed therein and therearound, a collar loosely mounted and confined in said groove, a forked member pivotally secured to said collar, a ratchet rotatably mounted in said forked member, a pawl for engaging said ratchet mounted on and movable with said forked member, and a connecting rod secured to and rotated by said ratchet, the said connecting rod reciprocated by rotation of said crank disk and pin.

3. In a lapping machine a crank disk, a crank pin mounted thereon and provided with an angularly disposed groove therearound, a collar loosely mounted and confined in said groove, a member pivotally mounted on said collar adapted to be oscillated thereby, a pawl mounted on said member and movable therewith, and a ratchet rotatably journaled in said member and engaged by said pawl.

4. In a lapping machine, a crank pin having an angularly disposed circumferential groove therearound, a collar loosely mounted

ed in said groove to permit rotation of said pin therein, a forked member extending around said collar in the plane thereof and pivotally mounted thereon at opposite points on the periphery thereof, a connecting rod rotatably mounted in said forked member and extending radially from said collar, a ratchet mounted on said connecting rod and a pawl mounted on said forked member for engagement with said ratchet, the said collar oscillated by the action of said crank pin groove during operation of said crank pin and reciprocation of said connecting rod, whereby said forked member and pawl are oscillated to impart a step by step rotation to said connecting rod through said ratchet.

5. In a lapping machine, a crank element, means mounted on said crank element for oscillation thereby in a path at substantially right angles to the path of said element, a connecting rod, and means coupling said connecting rod to said oscillatory crank element operated means, the said connecting rod adapted to be reciprocated by said crank element, and the said coupling means oscillated by said crank element mounted means to impart a step by step rotation to said connecting rod.

6. In a lapping machine, a crank element, means mounted on said crank element for oscillation thereby in a path at substantially right angles to the path of said element, a connecting rod pivotally coupled to said means, and a universal connection mounted at the free end of said connecting rod, the said connecting rod adapted to be reciprocated by said crank element and rotated by said oscillatory crank operated means, and the said universal connection permitting coupling of the free end of the connecting rod to the work to be lapped without alining said connecting rod therewith.

7. In a lapping machine, a crank element, means mounted on said crank element for oscillation thereby in a path at substantially right angles to the path of said element, a connecting rod, and means coupling said connecting rod to said oscillatory crank element operated means, the said coupling means formed to translate the oscillatory motion applied thereto, to a step by step rotation of said connecting rod.

8. In a lapping machine, in combination, a crank element having an angularly disposed guideway therearound, means mounted on said crank element for oscillation by said guideway during operation of said crank element, and a connecting rod pivotally coupled to said oscillatory means, the said oscillatory means adapted to rotate said connecting rod step by step in one direction.

HERMAN A. ERICKSON.
